UNITED STATES PATENT OFFICE.

ROBERT FIELD, OF HUDDERSFIELD, ENGLAND.

TOTALIZING MECHANISM FOR CASH-REGISTERS.

1,250,444.

Specification of Letters Patent. Patented Dec. 18, 1917.

Application filed April 23, 1917. Serial No. 163,851.

To all whom it may concern:

Be it known that I, ROBERT FIELD, a subject of King George V of Great Britain, residing at Huddersfield, in the county of 5 York, England, have invented a new and useful Improvement in Totalizing Mechanism for Cash-Registers, of which the following is a specification.

This invention relates to totalizing mech-

10 anism for cash registers of the key operated type and more particularly to the type of cash registers described and claimed in United States Letters Patent of myself, No. 1,149,908, August 10th, 1915.

15 The primary object of my invention is to provide improved means whereby, in conjunction with the mechanism employed for exhibiting the amount of each purchase, the amounts indicated, whatever number of keys 20 be depressed at one time or simultaneously in each registering operation, shall be totalized after each transaction so that the total amount taken can at any time be ascertained at a glance.

25 According to my invention I employ in conjunction with vertically movable indicating slides or tablets which are lowered to indicate the amount of each transaction, as in the type of cash register referred to, two 30 separate sets or series of wheels or notched or studded disks mounted on separate shafts arranged in axial alinement, one shaft and set of wheels for the silver and one for the copper, the operation of the tablets by the 35 depression of the keys causing levers actuated thereby to place devices in the path of pawl levers which said devices on the tablets being raised to normal position, engage and oscillate the pawl levers and thereby par-

40 tially rotate the respective toothed wheels to the desired extent and give a proportionate movement to the respective shaft whereby the amount of the last transaction is added to the previous total registered or totalized, 45 transfer mechanism operating between the copper and silver banks to transfer the required units of pence or shillings to make a unit of the next higher denomination to the silver bank or to a pounds counter or device.

50 Totalizing mechanism of the pawl and ratchet type and with means to transfer amounts from a lower to a higher denomination are commonly employed in cash registers, my improvements being especially intended for cash registers of the type described in the specification of the patent

referred to and designed principally to admit of any number of keys in each bank being depressed simultaneously and secure the totalizing of each transaction accurately. 60

The object and nature of the invention thus set forth will appear more fully from the accompanying description and drawings and will be particularly pointed out in the claims. 65

Figure 1 is a cross section taken on line 1—2 of Fig. 2 of a key operated cash register showing a unit of my improved adding mechanism applied thereto;

Fig. 2 is front elevation looking in the direction of arrow X of the totalizing mechanism detached;

Fig. 3 is a cross section, taken on line 3—4 of Fig. 2, showing the transfer mechanism for halfpence; 75

Fig. 4 is a cross section taken on line 5—6 of Fig. 2, showing the mechanism for transferring given amounts from the copper to the silver bank;

Fig. 5 is a cross section taken on line 7—8 of Fig. 2, showing the mechanism for transferring given amounts from the silver bank to the pounds counter device; 80

Fig. 6 is an end elevation, partly in section, of the lever and cam device for bringing the indicating mechanism to zero, and for releasing the keys or locking them in normal position, and 85

Fig. 7 is a detail hereinafter referred to.

Referring to the drawing and firstly to Fig. 1, A represents the side frames and part of the inclosing casing of a cash register of the key operated type and B one of the keys whose depression by the pressure of the finger on its outer end causes through a connection C, a tumbling lever D pivoted at E on internal cross framework, to be oscillated and through pin connections with upper and lower slides F. G to withdraw slide F from the path of a projection H on a respective long indicator tablet I of which there are a series carrying indications of increasing numerical value. The withdrawal of the slide F and the projection of the slide G at the same time into the path of the projection H allows the tablet to drop in its slides to present the indication of the key value to view. The indicators are returned to zero position and the parts reinstated in normal position by a transverse vertically sliding bar J (see Fig. 6) which has uprights K carrying one way pawls L for engagement by a yoke M 95 100 105 110

actuated by a cam *N* on a cross shaft *O* which is operated by a hand lever *P*. The yoke could be actuated by a "no sale" key or other part of the mechanism of the cash register instead of by hand lever.

With the exception of slight detail alterations and the employment of the cam *N* actuated by the hand lever *P* and yoke *M* the parts described are arranged and operated 10 substantially as shown and described in my prior United States Patent No. 1,149,903.

My invention consists in applying to cash registers of the type referred to improved means adapted to be actuated on each operation of a key or a series of keys simultaneously to totalize the amount of the transactions so that the total amount of cash taken can at any time be ascertained at a glance.

According to the invention, I employ two separate shafts or spindles *a*, *b* supported in axial alignment across the machine and journaled in suitable bearings in the framework, the shaft *a* being provided for the copper bank or set, and the shaft *b* for the silver bank or set. Fast on the shaft *a* are a series of toothed wheels or notched or studded disks *c*, one for each key *B*, of which latter there may be any desired number according 25 to the combinations used in obtaining any amount from one penny upward to one shilling, as for instance, the keys employed in this case represent respectively 1d., 2d., 3d. and 6d. There is also fast on said shaft a total indicating disk *d* bearing on the periphery two or more sets of numerals from zero to 11. In this instance four sets of numerals from zero to 11 are provided on the disk. Close on the opposite end of the shaft 30 *a* is a toothed wheel or notched or studded disk *e* for the key for registering halfpence.

On the shaft *b* are mounted similar toothed wheels or notched or studded disks *f* for the keys in the silver bank or set of which also 45 there may be any number according to the combinations of amounts desired as for instance, in this case there is a key for (one shilling) 1/-; one for (two shillings) 2/- and one for (ten shillings) 10/- there being provision in the registering mechanisms in the specification of the patent before referred to for multiplying any of these amounts, say, three times, by three distinct 50 operations or depressions of their respective keys. Each toothed wheel or disk *f* in the silver bank, with the exception of the wheel *f*, *a*, for the 10/- key, is fast on the shaft *b*. On the shaft *b* is a total-indicating disk *g* for amounts from zero to nine, or zero to 55 nineteen as may be preferred. In the arrangement shown, the disk *g* has four series of numerals running from zero to nine, on its periphery.

A separate counter device *h* is provided 60 for pounds, this being adapted to be actu-

ated from the wheel or disk employed in connection with the (ten shillings) 10/- key and from the silver bank, as will be herein-after described.

Engaging with a pin or stud *i* on each 70 individual indicator tablet *I* is the forked end of a lever *j* pivoted on a pin or transverse spindle *k*. The opposite end of said lever is enlarged and has pivoted thereon a trip or tumbling or like lever *l* normally 75 resting at its tail end on a stud *m* projecting from the lever *j* and which at each depression of the respective key to bring about the descent of the indicator tablet to indicating position, is caused, by the oscillation 80 of the lever *j*, to wipe idly over the near end of a lever *n* pivotally mounted on the respective shaft *a* or *b* adjacent the toothed wheel corresponding to the respective operating key *B*.

On the outer arm of the said lever *n* is pivotally mounted a pawl or push finger *o* which is adapted on actuation of the said lever *n*, to engage with a tooth of the respective toothed wheel *c* or *f* and turn it in one 90 direction a distance equivalent to one, two or more teeth according to the number of pence or shillings represented by the key and as determined by the extent of movement of the indicator tablets *I*. The operation of said toothed wheels *c*, *f* is effected when the indicator tablets are returned to their normal or zero positions and the mechanisms are so timed that the operations take place successively, commencing at the highest figure in the bank or set. For the operation of the totalizing mechanism the hand lever *P* is first moved over in the direction of the arrow *R* in order to remove a locking slide *S* from locking position under the several keys, as described in the specification of my patent before mentioned, the yoke *M* engaging a bell crank lever *T* and through the same moving said slide endwise as ordinarily. This locking slide forms no part 105 of my present invention.

When the hand lever *P* is drawn fully over toward the operator, the keys are free to be depressed and as they are forced downwardly either singly or any number thereof simultaneously the descent of the respective tablets *I* rock the respective levers *j* the enlarged ends of which are thus elevated. As the said enlarged ends of the levers move upwardly, they carry the trip or tumbling 115 levers *l* with them, the outer ends of said levers wiping idly over the near ends of the levers *n* and on passing clear of the same assuming a position above and in the path thereof. After the depression of the keys 120 to give indication of the amount of the purchase the hand lever *P* is returned to normal position and no action takes place in respect of the totalizing mechanism, but when the said hand lever is again drawn forward 130

preparatory to registering the next transaction the cam *N* elevates the yoke *M* and raises the lowered tablets to their zero position in doing which the respective levers *j* are rocked correspondingly, the descent of the enlarged ends thereof causing the trip or tumbling levers *l* to engage with the upper edges of the respective pawl carrying levers *n* and, by virtue of being held by the 10 studs *m* on said levers, cause the levers *n* to be rocked about their pivot centers whereby the pawls carried thereby advance the respective toothed wheels a distance equivalent to the denomination of the key, 15 that is to say, the single pence wheel is advanced a single tooth, the 2d. and 3d. wheel a distance equivalent to two teeth and three teeth respectively and the 6d. wheel a distance equivalent to six teeth, the combined 20 movements of the wheels transmitting through the shaft *a* to the total-indicating disk *d* a movement equivalent to the total of the units of the several wheels thus advanced.

25 In the silver bank the same operations take place but, in this case, the keys may be depressed one, two or three times to give the amount of the key value or two or three times such an amount as in the specification 30 of my patent before referred to, the second or third depressions of the keys causing the tablets to descend farther by one or more steps. In order to transmit the added motions to the toothed wheels of the silver bank, I provide on the enlarged ends of the 35 levers *j* a series of say, three trip or tumbling levers *l* (see Fig. 7) one, two or all of which are thus elevated above the ends of the pawl levers according as the key is 40 depressed one, two or three times these trip or tumbling levers, if there be more than one elevated, operating therefore on the respective pawl lever in successive order as the respective tablet is raised to its normal position 45 whereby one, two or three successive oscillations is or are given to said pawl levers and the respective toothed wheel rotated to an extent to move it a distance equivalent to 1/- 2/- or 10/- or to twice 50 or three times such amounts.

With respect to the registration of half-pence, the respective toothed wheel *e* is loose upon the shaft *a* and has on one face thereof a series of pins *p* spaced at distances 55 apart equivalent to two teeth. As the wheel *e* is rotated the said pins in turn successively engage with a finger *q* (Figs. 2 and 3) on a short spindle *r* and rock the same, a second finger on said spindle engaging 60 with the pawl lever *n* of the pence wheel and elevating said lever sufficiently to cause its respective pawl to move the pence wheel one tooth. In order to indicate half-pence, the pins *p* successively engage with a lever *s* 65 and rock a shaft *t* on the outer end of which

is a half-moon or like device *u* having on its face the representation of a half penny and a blank portion, said device occupying a position adjacent the total-indicating disk *d*. Each odd half-penny registered is thus indicated by the position of this device presenting the representation of the half-penny opposite the pence on the total-indicating disk *d* but on registration of each second half-penny the blank on the device on the 70 transfer spindle or shaft *t* is brought opposite the figure in pence on the total indicating disk *d* and simultaneously therewith the pence wheel is moved to the extent of one tooth. Loosely mounted on the shaft *b* 80 is a sleeve *v* carrying at one end the toothed wheel *f* adapted to be partially rotated on depression of a key representing 10/- in the same manner as has already been described with reference to the keys of lower 85 value. The opposite end of the sleeve *v* carries a toothed wheel *w* and a "digit" disk *x* which latter lies adjacent to the numerator disk *g* of the silver bank as shown at Fig. 2. The periphery of the "digit" disks 90 *x* is divided into spaces corresponding to those on the numerator disk *g* and every alternate one of these spaces is marked with a "1" and each neighboring space is blank. Loosely mounted on a fixed spindle *y* is an 95 arm *z* (Figs. 2 and 5) having a pin 2 projecting into the path of and adapted to be engaged by a series of abutments 3 on the disk *g*. These abutments are four in number, corresponding to the four series of numerals (zero to nine) on said disk, and are so arranged that each time a numeral nine passes a given point the respective abutment engages the pin 2 and rocks the arm *z*. The 100 said arm carries a pawl 4 adapted to engage the teeth of the wheel *w* and each actuation of the arm causes the said wheel to be rotated a distance equal to one tooth, thereby rotating the digit disk one space and bringing a marked space opposite a 105 certain point in the periphery of the numerator disk *g*, or presenting a blank opposite thereto. The wheel *w* has a series of projecting pegs 5 which are adapted to engage a finger 6 on a sleeve 7 loosely mounted 110 on the spindle *y*, the other end of said sleeve carrying a counter arm 8 adapted to engage and actuate the star wheel 9 of the "pounds" counter. The pins on the wheel *w* are provided opposite every second tooth, 115 so that rotation of said wheel, either directly from the 10/- key or from the disk *g* will cause the "pounds" counter to be actuated each time the wheel *w* moves two teeth. If the 10/- key is depressed once or 120 three times, giving an odd amount of 10/-, this will be indicated by the presentation of a "1" in front of the amount displayed by the total-indicating disk *g* of the silver bank, or if the amount of silver already 125 130

- indicated exceeds 10/- then such actuation of the 10/- key will cause a digit mark "1" to be removed from opposite the indication of the disk *g*, the completed pound being transferred to the pounds counter. 5 Similarly if the rotation of the total-indicating disk *g* is such as to carry it past the last figure of one of its four series, then the digit disk in its consequent movement will 10 either cause a "1" to be exhibited opposite the indication of the total-indicating disk or if the amount of silver displayed were already above 10/- then the rotation of the digit disk will remove the "1" from opposite 15 the total-indicating disk and cause the "pounds" counter to be operated to record an addition of one pound.

Transfers from the copper bank to the silver bank are effected as follows: The copper total-indicating disk *d* has a series of abutments 10, four in number corresponding to the four series of pence indications zero to 11 on its periphery. Extending into the path of, and adapted to be engaged by 25 these abutments 10 is a pin 11 on a weighted pivoted lever or arm 12. The upper end of this arm, on actuation thereof by one of the abutments, is adapted to bear against and rock on its pivot 13, an arm 14 having a 30 cranked portion 15 adapted to bear against the rear end of the pawl arm *n* of one of the toothed wheels *f* on the shaft *b* of the silver bank. The rocking of the arm 12 by one of the abutments, on the disk *d* passing the last 35 numeral of any one of its four series, causes the arm 14 to swing on its pivot until the upper end of the said arm 12 slips into a V-shaped notch 16 on the arm 14, thereby holding said arm in such a position that it 40 can be engaged by the free end of a curved rocking lever 17, when said lever has a pivotal movement imparted to it. This pivotal movement of the lever 17 is brought about by means of the shaft *O* which is 45 rocked at each movement of the hand lever *P* to its normal position. A finger 19 on the shaft *O* is adapted, in one direction of movement, to move idly under a swinging latch 20 on the lever 17, and in the other 50 direction of movement to engage the latch and swing the said lever on its pivot so that if the arm 14 has been positioned by the arm 12, the said arm 14 will be engaged by the lever 17 and the pawl arm *n* actuated to 55 move the respective toothed wheel *f* one tooth, thereby partially rotating the shaft *b* and advancing the silver total-indicating disk *g* one unit.

Any suitable known devices such as V 60 toothed wheels or disks, may be employed to prevent "overthrowing" of the toothed wheels *c*, *f* or *f'* and to cause the indications of the respective total-indicating disks to be presented in exact alinement.

65 Slots are formed in the inclosing casing

on a line parallel with the shafts *a*, *b* through which the totals are exhibited.

If the parts have to be brought to zero at the end of each day's takings, the counter would be replaced by a total-indicating disk 70 or disks so that said disks could be turned forward by hand along with the numerator disks *d*, *g* and *x* to place the whole of them at zero.

The parts are so arranged or timed that 75 the totalizing operations take place successively commencing at the highest figure in each respective bank.

Suitable springs retract the pawl carrying levers *n* after each actuation thereof, 80 stop pins 21 limiting the return movement of said levers.

In employing my improved totalizing mechanism in the type of key operated cash registers hereinbefore referred to, any 85 amount of purchase registered can be totalized after each transaction, whatever number of keys are actuated in making the registration and whether they are all depressed simultaneously or otherwise, this being of 90 considerable advantage as ordinarily in totalizing mechanisms the depression of more than one key or given combination of say two keys at a time, causes the parts to jam and render the machine for the time being 95 inoperative.

It will be understood that the means for actuating the toothed wheels or notched or studded disks and for transferring motion from the pence to the silver bank or from 100 the half-pence to the pence numerator or from the 10/- to the pounds counter or shillings numerator, may be varied or modified without departing from my invention.

Having thus described my invention, what 105 I claim as new and desire to secure by Letters Patent is:—

1. In a cash register, a series of vertically and independently movable indicating slides, a series of pivoted levers operated by 110 the said slides and each provided with a pivoted trip, a revoluble total indicating disk common to the series of slides, a series of ratchet mechanisms operatively connected with the said disk and arranged to be operated by the trips in a predetermined order when the levers are moved in one direction only, and means for moving the indicating slides to their zero positions simultaneously and thereby actuating the ratchet mechanisms and the total-indicating disk. 115

2. In a cash register, a series of vertically and independently movable indicating slides, a series of levers operated by the said slides, each of the said levers being provided 125 with a series of trips pivoted to it and arranged circumferentially of its pivot, a series of ratchet mechanisms operatively connected with the said disk and arranged to be operated by the trips in a predetermined 130

order when the levers are moved in one direction only, the trips of each series being moved into operative position one after another according to the number of indicating movements of the slide to which they pertain, and means for moving the indicating slides to their zero positions simultaneously and thereby actuating the ratchet mechanisms and the total-indicating disk.

10 3. In a cash register, a series of vertically and independently movable indicating slides, a series of pivoted levers operated by the said slides and provided with pivoted trips, two revolute shafts arranged in alignment and provided with total-indicating disks for copper and for silver respectively, a series of ratchet mechanisms on each of the said shafts and operating the disk pertaining to it, the said ratchet mechanisms being operated by the trips in a predetermined order when the levers are moved in one direction only, transfer mechanism operatively connecting the two said shafts, means for exhibiting odd amounts of silver arranged adjacent to the total-indicating disk for silver, a counter for gold, means for transferring the requisite units of the last said disk to the said counter, means for exhibiting fractional units of copper arranged adjacent to the total-indicating disk for copper, means for transferring the said fractional units to the total-indicating disk for copper, and means for moving the indicating slides to their zero positions simultaneously and thereby actuating the ratchet mechanisms and the total-indicating disks.

20 4. In a cash register, a series of vertically and independently movable indicating slides, a series of pivoted levers operated by the said slides and provided with pivoted

trips, two revolute shafts arranged in alignment and provided with total-indicating disks for copper and for silver respectively, a series of ratchet mechanisms on each of the said shafts and operating the disk pertaining to it, the said ratchet mechanisms being operated by the trips in a predetermined order when the levers are moved in one direction only, transfer mechanism operatively connecting the two said shafts, means for exhibiting odd amounts of silver arranged adjacent to the total-indicating disk for silver, a counter for gold, means for transferring the requisite units of the last said disk to the said counter, means for exhibiting fractional units of copper arranged adjacent to the total-indicating disk for copper, means for transferring the said fractional units to the total-indicating disk for copper, and means for moving the indicating slides to their zero positions simultaneously and thereby actuating the ratchet mechanisms and the total-indicating disks. 55

In testimony whereof I affix my signature in the presence of two witnesses.
